MULTIPOSITION SWITCH

Robert H. Bentley, Hartford, Conn., assignor to
 The Arrow-Hart & Hegeman Electric Company,
 Hartford, Conn., a corporation of Connecticut

Application October 31, 1947, Serial No. 783,308

13 Claims. (Cl. 200—6)

1

This invention relates to improvements in electric switches and more particularly switches in which the movable contact member is capable of occupying several positions.

It is an object of my invention to provide a novel structure of a multi-position switch in which the parts may be of separate form and inexpensively manufactured and in which the assembly costs will be kept at a minimum in accordance with the liability of operation.

Another object of the invention is to provide a switch of the foregoing type in which the movable contact is maintained in its different positions resiliently, but from which it may be moved without great effort and without need of overcoming undue frictional forces.

Other objects and advantages of the invention will occur as it is described in the accompanying drawings.

In the drawings:

Fig. 1 is a plan view of one form of switch mechanism embodying the invention, with the cover plate and operating lever removed;

Fig. 2 is a longitudinal elevational section view taken along line 2—2 of Fig. 1;

Fig. 3 is a longitudinal sectional view taken along line 3—3 of Fig. 1;

Fig. 4 is an exploded perspective view of certain parts of the movable contact operation means;

Fig. 5 is a plan view similar to Fig. 1 of another form of the invention;

Fig. 6 is a longitudinal elevational view taken along line 6—6 of Fig. 5;

Fig. 7 is a longitudinal elevational section view taken along line 7—7 of Fig. 5; and

Fig. 8 is an exploded perspective view of the bridging contacts and their carrying means.

Referring to the drawings, the switch mechanism is mounted upon and mainly housed within an insulating casing 10, preferably of moulded insulating material. The casing is hollowed out to form three parallel longitudinal chambers 12, 14 and 16 of approximately equal width. The two outer chambers 12 and 14 are, or may be deep, extending fully to a thin bottom wall of the casing. The central chamber 16 is preferably of less depth, being approximately one-half the depth of the other two chambers. The central chamber has its side walls divided at their middle part by U-shaped bearing passages to receive cylindrical bearing bosses 18 and 22.

The bosses 18 and 22 are alike and preferably made of insulating material with reduced axial circular extensions (19 and 23) extending from

one end thereof. These extensions seat in U-shaped recesses in the inside of the outer walls of the outer chambers 12 and 14. Thus, the bosses 18 and 22 at one end are supported for axial rotation by the recesses in which the extensions 19 and 23 seat, and at the other end by the recesses in the walls between the inner chamber 16 and outer chambers 12 and 14.

Movable bridging contacts are carried by the bosses 18 and 22, being mounted thereon at the shoulder between or juncture of the reduced ends (19 and 23) with the main portion of the bosses. The illustrated movable bridging contact members 26 and 30 are alike, being preferably stamped from thin, flexible sheet metal into the form best indicated in Fig. 4, wherein it may be observed that arms 31 and 32 extend obliquely from a round central portion. In order to cause the bridging contact to move with the boss on which it is mounted, oppositely extending radial lugs, such as 24, are provided on the extensions 23 and 19. The lugs and their associated extension fit within a complementary recess, such as 33, in the bridging member. To space the bridging contacts from the inside surface of the outer walls of the chambers 12 and 14, washers, such as 34, are placed on the extensions, between the outer wall of the chamber and the bridging contact.

A number of stationary contact members are 30 or may be located in each of the chambers 12 and 14. Preferably these contacts are three in number, being located at opposite ends of the casing and in the bottom of the casing at the middle. The end contacts which may be similar, are designated generally by the numerals 36, 38, 40 and 42. They have vertical portions such as 36a (referring to Fig. 3) whose edges are slidably received in slots 15 and 17 (Fig. 1) formed in opposite walls of the chamber 14 at the ends thereof. By this means it is possible to slide the vertical portion (such as 36a of the contact 36) into position at the end of the chamber. The fixed contacts (referring for example to contact 36) have a contact portion, such as 36b, extending from and bent at right angles to the vertical portion 36a adjacent the top edge of the casing 10 and lying along the inside surface of the outer wall of the chamber 14 in position to be engaged by the end of the arms 32 of the movable contact 26. For the purpose of attaching conductor wire, a terminal portion 36c extends from the top of the vertical portion 36a of contact 36 and is bent in a direction to lie outside the casing 10.

Formed and mounted in like manner are the stationary contacts 38, 40 and 42. The contacts

40 and 42 are located in opposite ends of the chamber 12.

In the bottom of chambers 12 and 14 are central contacts, such as 39. These contacts may be stamped from sheet metal with terminal portions, such as 39a, extending through an aperture in the floor of the casing and contact portion, such as 39c lying within the chamber 12. These central contact members may be secured in position in any convenient fashion, such as by peening over a portion of the contact member lying outside the bottom of the casing. The contact portion 39c is in position to be engaged by the end of the arm 32 of the movable contact 30 when the end of the arm 31 engages the contact 38. When the end of the arm 32 engages the contact 38, the end of the arm 31 will engage the central contact 39. A similar engagement of the fixed contact 40 and 42 and the central contact in the chamber 12 takes place and is accomplished by the movement of the bridging contact 26.

In order to move the contact carrying bosses 18 and 22, I have provided a pair of metallic stampings, such as 50, which are mounted upon rectangular extensions, such as 20, on the inner ends of the bosses 18 and 22. The stampings are of circular shape, having a flange in which are formed recesses 51, 52 and 53 which are diametrically opposite to recesses 54, 55 and 56 respectively, so as to receive indexing balls 58 and 59 which are spring pressed by compression springs 63, into engagement with the stampings. The movement of the stampings conjointly and thereby movement also of the bosses 18 and 22 is accomplished by means of a lever or handle 60 mounted in a cylindrical mounting nipple 62 of a form now well understood in the art, the nipple being mounted upon a metallic cover plate 64 in conventional fashion and having a diametrical pivot pin 65 extending through the nipple on which the lever 60 is mounted. The inner end of the lever lies between the two stampings 50 and has passing transversely through it a small pin 61 whose ends are adapted to lie and move within radial slots 57 formed in the stampings 50. Thus, as the lever 60 is moved from mid-position as shown in Fig. 2 to the right or to the left, the engagement of the pin 61 with the sides of the slot 57 will cause the stampings 50 to rotate and also turn the bosses 18 and 22, thereby operating the movable contact members into and out of their three different positions. It will be noted that in the mid-position, as illustrated in Fig. 3, the movable contact is disengaged from all of the stationary contacts.

The balls 58 and 59 and their springs 63 are located in opposite ends of the center chamber 16.

In order to hold each spring and its ball in the bottom of the chamber in which they are located, I have provided a stamped sheet metal frame, designated generally by the numeral 70, over each spring and ball set. These frames have a horizontal bar portion 71 overlying the spring 63 and at the outer end thereof a vertical portion bent down to the bottom of the chamber. Extended upwardly from opposite sides of the bar at each end are parallel lugs, such as 72, which rise to the top of the casing and are thus held within the chamber 16 by the insulating cover plate 73 which underlies the metallic cover plate 64.

In Figs. 5-8 another form of the invention is illustrated in which a casing 100, similar to the casing 10, is utilized and spring-pressed index-

ing balls and retaining frames are housed therein, similar to those in the previously described form.

As in the previously described form, stationary contacts may be located in the four corners of the casing at the ends of the outside chambers 112 and 114. Such contacts may be stamped L-shaped members, such as 136, the long leg of which may extend through the floor of the casing to provide a wire terminal 136b. Preferably the stationary contact members are seated in L-shaped shallow recesses 117 so that only the side face of the members projects slightly beyond the inside wall of the chamber in position to be engaged by the ends of the arms of the bridging contact members 130.

As illustrated in Figs. 5-8, the bridging contact is of similar shape to the bridging contact 30 in the previous form. It will be understood, however, that the bridging contact in each form may be of different configuration depending entirely upon what contacts it is desired shall be engaged by the bridging contact in the several positions of the switch mechanism.

Although a central contact on the floor of the switch casing in the shape illustrated in the previously described form of the invention may be used, a central contact of different form may be employed for some uses of the switch. Thus, in Figs. 5-7 there is illustrated a central contact having a bar-shaped contact portion 139 lying along the inside wall of the chamber 114 at the bottom thereof. A transverse connecting portion 140 extends from the middle of the top edge of the contact 139 transversely across the base in a channel 141 in the middle of the casing and at the bottom thereof. At the opposite side of the casing from the contact portion 139 the connecting portion joins another connector portion 142 which is bent up at a right angle from the transverse part 140 and extends horizontally for a short way along the inside surface of the outside wall of the chamber 112 toward its right end (Figs. 5 and 6). Thereupon it connects with one end of an inverted U-shaped portion 143 whose other end may extend through a slot in the bottom of the chamber 112 at its right end to form a wire terminal portion 144. If desired, the terminal end of the inverted U portion may be offset slightly in an outward direction so as to lie within a shallow recess, such as 117. Such offsetting may be particularly advantageous if the casing is molded symmetrically throughout.

By making the casing symmetrical, it is possible not only to use the form of central contact just described, but it is possible also to use stationary contacts at the ends of the chamber 112 of the same form as illustrated (in Fig. 7) at the ends of the chamber 114, when desired.

Referring to the form of central contact as illustrated in Figs. 6 and 7, it will be understood that when the bridging contact is moved from the position of Fig. 7 in either a counterclockwise or a clockwise direction, the ends of its arms 132, 131 will either engage the fixed contact 136 and the left end portion of the central contact 139 (respectively) or the right end portion of the central contact and the fixed contact 138 (respectively). In the mid position as shown in Fig. 7, the bridging contact is disengaged from all of the fixed contacts.

The means for operating the bridging contact, although similar in general characteristics to the form of invention previously described, has cer-

tain structural differences which will now be pointed out.

A switch spindle 118 of square or other non-circular cross-section, extends transversely across the middle of the casing and has circular ends 119 seating in U-shaped bearing recesses in the inside surfaces of the outside walls of the chambers 112 and 114, adjacent the top edges thereof. Mounted on the center of the spindle 118 is a metallic disc 150 having recesses 151, 152 and 153 in the periphery thereof to receive the spring pressed indexing balls, such as 161 and 162. A radial slot 157 is formed in the periphery of the disc member 150 and receives a transverse pin 166 mounted in the end portion of a centrally-located short rod 167 which extends out from and above the casing 160. For operating the switch mechanism and for moving the rod 167, an operating button or handle 160 which is or may be of cylindrical form and made from insulating material is molded or mounted upon the upper end of the rod 167. The operating button is slidably mounted upon a metallic mounting and cover plate 164. That plate has a centrally located slot 165 running longitudinally with respect to the casing to permit passage therethrough and sliding movement therealong by the rod. This cover plate 164 is secured over the casing by means of bolts threaded into tabs or lugs 168 which extend from the ends of the plate 164 and are offset downwardly so as to space the plate 164 from the top surface of the casing and slightly above an insulating cover plate 173 located between the casing and the metal cover plate 164. A slideable rectangular metal plate 170 is fixedly secured in any suitable manner on the rod 167 under the cover plate 164 in such manner as to slide over the under surface of said cover plate 164. In order to guide the sliding movement of plate 170 and thus to guide the sliding of the rod 167 and operating member 160, the side edges of the plate 164 are, or may be bent down as at 169 so that the side edges of the slide plate 170 slidably engage said bent down edges.

From the foregoing it may be observed that the operating member 160 may be moved from the position illustrated in Figs. 6 and 7 to the right or to the left by a sliding motion. Such motion will cause clockwise or counterclockwise rotation of the spindle 118 and disc member 150 carried thereby by reason of the engagement of the transverse pin 166 in the slot 157. In order that this rotation of the spindle may be imparted to the movable contacts, insulating discs 180 having square central apertures are slidably mounted on the spindle 118 on opposite sides of indexing and operating disc 150. On opposite sides of these discs 180, movable bridging contacts, such as 180, are located. These contacts are generally similar in form to the bridging contact 30 in the form previously described. In order to translate movement of the spindle and discs 180 to the movable contacts radially extended lugs, such as 184, are bent at right angles to the plane of the bridging contact to lie within peripheral notches, such as 181, in the discs 180.

From the foregoing it will be observed that I have provided different but related forms of a switch mechanism in which the movable switch operating parts may be moved into three positions in each of which they are resiliently held by the spring pressed ball indexing means described. The parts of the invention are all small and relatively inexpensive to manufacture and

assemble, yet their resulting combination is a switch capable of controlling low power circuits effectively.

Many modifications within the scope of my invention will occur to those skilled in the art. Therefore I do not limit it to the specific forms illustrated.

What I claim is:

1. In a multi-position switch, an insulating casing having parallel chambers with bearing recesses in the walls thereof, insulating bosses rotatively supported across said chambers in said recesses, movable contact members carried by said bosses adjacent the walls of said chambers, stationary contacts engageable by said movable contacts and slidably mounted in slots in the walls of said chambers, in combination with means to move said bosses and contacts simultaneously comprising an operating lever extending into said casing, a pair of oppositely facing metal stampings engaged with said bosses for simultaneous rotation, laterally extending means on the end of said lever engaging in slots in said stampings to cause rotation of said stampings when said lever is moved, and indexing balls and springs seated in one of said chambers with said balls engaging recesses on the peripheries of said stampings to releasably hold the stampings in one or another of several switch positions.
2. In a multi-position switch, a casing having three parallel chambers, stationary contact means in certain of said chambers, movable contacts engageable with said stationary contacts, springs and indexing balls in the middle chamber, a rotary member having peripheral recesses engaged by said balls to hold said rotary member releasably in three switch positions, retaining means over said springs and balls to hold them in said middle chamber, operating means outside said casing extending therein, means transversely extending from the operating means and engaging in a slot in said rotary member for causing rotation thereof as said operating member is moved, and means extending transversely of said chambers supporting said rotary member and journalled in bearing recesses in the walls of said chambers, said transversely-extending means engaging with said movable contacts to operate them in response to movement of said operating means.
3. In a multi-position switch, an insulating casing having three parallel chambers, movable contacts in the outside chambers, fixed contacts at the ends and bottom of said chambers for engagement by said movable contacts, each movable contact having supporting and operating means comprising an insulating boss rotatively supported in bearing recesses in the walls of said chambers, a shoulder on said boss by which said movable contact is held adjacent a wall of the chamber, said movable contact and boss being keyed for joint rotation, indexing means in the middle chamber, means turning with said bosses and having peripheral recesses engaged by said indexing means releasably to hold said movable contacts in any of three positions.

4. A multi-position switch as claimed in claim 3 having its bridging contact in angular form to disengage all fixed contacts in a mid-position of the switch, and to engage one end contact and a bottom contact in positions on either side of said mid position.

5. A multi-position switch as claimed in claim 3 wherein the means turning with said bosses comprise identical metal stampings placed face

to face and keyed to different bosses for joint rotation therewith.

6. A multi-position switch as claimed in claim 5, having an operating member extending into the casing, said stampings being formed to provide entrance therebetween of the inwardly extending end of said operating member and having radial slots, means extending transversely at the end of said operating member for engagement with said slots for moving said contacts.

7. A multi-position switch as claimed in claim 6 having indexing balls and springs in the middle casing chamber engaging at opposite sides of said stamping into peripheral recesses to hold the switch releasably in one or another of three positions.

8. A multi-position switch as claimed in claim 3 wherein the means turning with said bosses comprise identical metal stampings placed face to face and keyed to different bosses for joint rotation therewith, and indexing balls and springs in the middle casing chamber engaging at opposite sides of said stamping into peripheral recesses to hold the switch releasably in one or another of three positions.

9. A multi-position switch as claimed in claim 3 wherein the means turning with said bosses comprise metal stampings keyed to different bosses for rotation therewith, said stampings having slots and being formed to provide a space therebetween for entrance of an operating member, and a pivoted operating member having an end extending into said space, a transverse pin on said end entering said slots and causing both said stampings to rotate simultaneously.

10. In a multi-position switch, an insulating base having three parallel chambers, fixed contacts at the ends and in the bottom of the outer chambers, angular movable contacts engageable with certain of the fixed contacts, in combination with supporting and operating means for the movable contacts comprising circular rotary insulating members keyed to said movable contacts for rotation in unison therewith, an indexing

member between said insulating members turning in unison therewith, indexing balls and springs in the middle base chamber pressing on opposite sides of said indexing member into peripheral recesses therein to hold the switch releasable in one or another of three positions, an operating member extending into the base and having a transverse part slidably engaging with a slot in said indexing member to cause rotary movement thereof as said operating member is moved.

11. In a multi-position switch as claimed in claim 10 wherein the means which causes the indexing member and the rotary contact-carrying members to turn in unison is a spindle having non-circular section passing through similarly-sectioned apertures in said rotary and indexing members.

12. In a multi-position switch as claimed in claim 10, wherein the operating member is a slidably mounted member, a plate overlying the base over the surface of which said operating member slides, and means connected with said operating member and sliding beneath said plate and holding said operating member on said plate.

13. In a multi-position switch as claimed in claim 10, a mounting plate overlying the base and having a slot through which said operating member projects, said mounting plate being spaced from the top surface of the base, and a slidable guide plate beneath said mounting plate connected with said operating member.
